OIL FLOW SWITCH HAVING PIVOTED CUP-SHAPED ACTUATOR

Bertil H. Clason, Flint, Mich., assignor to General Motors Corporation, Detroit, Mich., a corporation of Delaware
Filed Aug. 9, 1963, Ser. No. 300,975
7 Claims. (Cl. 200—81.9)

This invention relates to electrical switches and more particularly to an electrical switch which is responsive to fluid flow.

It is an object of the present invention to provide an electrical switch that, when combined with an indicating circuit, will notify a driver of a flow condition in his oil system.

It is a further object of the present invention to provide a switch which can be submerged in a fluid whose flow is being monitored.

It is still a further object of the present invention to provide a simple flow responsive electric switch with a minimum number of moving parts.

It is yet a further object of the present invention to provide a switch that can be easily mounted in a variety of locations in an oil system.

Further objects and advantages of the present invention will be apparent from the following description, reference being had to the accompanying drawings wherein a preferred embodiment of the present invention is clearly shown.

In the drawing:

The single figure drawing is a sectional view of a switch made in accordance with this invention illustrated controlling a typical warning type of electrical circuit.

Referring now to the drawing, a terminal 10 is mounted in a terminal holder 12 composed of any well-known insulating material. The terminal holder is firmly engaged with a metallic switch body 14 by being lodged between a surface 16 of the switch body 14 and a rolled-over flange 18 of the switch body 14. The terminal 10 has a portion extending into the switch body forming a contact 20. On the opposite end of the switch body from the terminal entry point is an aperture 22 through which a contact pin 24 is slidably disposed. The contact pin 24 has a retaining ring 26, said retaining ring having chamfered portion 28. One end of the contact pin 24 has a contact head 30, said contact head having an abutment 32 serving to retain a spring 34 in biased engagement with the contact head 30 and a wall portion 36 of the switch body 14. A substantially cup-shaped actuator 38 is biasedly held between a wall portion 40 of the switch body 14 and one surface of the retaining ring 26. The switch body 14 has a threaded portion 42 disposed to engage a threaded opening 44 of a fluid carrying container 46. The switch body 14 has an area 48 with flats thereon to facilitate the mounting of said switch to a threaded opening in a container.

In operation, the switch or the terminal 10 is connected in series with a tell tale light 50, an ignition switch 52 and a power source 54 to form an indicating circuit, the switch body being grounded as is one side of the power source.

The switch body 14 can be mounted in any convenient location in an oil system of an automobile. A pipe thread connection is established through a drilled and tapped hole in the oil system in a manner that will allow the connection to withstand up to 150 pounds per square inch of oil pressure at a temperature of from -60° to $+300^{\circ}$ F. without leaking. With the ignition switch 52 in the ON position and no oil flow being generated in the oil system, a circuit will be established in the aforementioned indicating circuit. With the ignition switch in the

2

closed position and the engine started, oil pressure would normally cause an oil flow through oil passage 60 and past the cup-shaped actuator 38, extending into the oil passage, to cause the breaking of the established circuit.

5 This is brought about by a movement of the oil in the passage 60 pushing against any side of the cup-shaped actuator 38, whereby the contact head 30 is levered out of its biased engagement with the contact 20 by an edge of the cup 38 pivoting on surface 40 of the body 14. More specifically, this is accomplished by the cup-shaped actuator being pushed in one direction and drawing its inside surface down against the chamfered portion 28 of the contact pin 24 as the actuator pivots on one of its edges. The contact pin 24 being loosely, slidably engaged with the aperture 22 is easily drawn away from the contact 20 thereby breaking the circuit therethrough.

The only metal to metal contact in this device is between the contact pin 24 and the body 14 and between the contact pin and the cup-shaped actuator 38. In view 20 of the loose fit of the contact pin 24 within the aperture 22, the oil being monitored can easily pass into the switch body through aperture 22 causing the aforementioned parts to be constantly lubricated.

Another advantage of this invention is that the actuator is responsive to flow against any side and so the mounting in the threaded part is simplified somewhat. Vane type flow switches require perpendicular alignment of the vane with the fluid passage.

The utility of this invention is apparent in that it enables the operator of a vehicle to be aware, through a medium of a tell tale lamp mounted in the driver compartment, of the actual flow of oil in the engine oil system. It is possible in automobile engines of present day design to have an oil pump creating an oil pressure but, due to 35 a blocked oil passage, to have no oil actually flowing in the oil system. An example of this situation is illustrated in the simple oil system in the drawing. A pump 56 of an engine 58 draws oil from a sump or crankcase 61 and moves the oil through a filter 62. If the filter 62 is blocked with engine sludge, no flow will occur in the engine but the pump 56 will continue to operate and pressure indications will remain at the pump outlet. Therefore, it is apparent that destructive engine wear could result due to no oil flow while a pressure gauge registered 40 normal pressure. This invention is meant to obviate this problem.

While the embodiment of the present invention, as herein disclosed, constitutes a preferred form, it is to be understood that other forms might be adopted.

50 What is claimed is as follows:

1. An electrical switch comprising a body, an insulated conductive means extending through a wall of said body, a contact means extending through another wall of said body disposed in biased engagement with said insulated conductive means forming part of an electrical circuit, and an actuator means including flow responsive means carried by said contact means, said actuator means being responsive to fluid flow whereby said conductive means and contact means are disengaged to 55 break the electrical circuit.

2. An electrical switch comprising a conductive path, said path including a conductive means and a contact means, said conductive means disposed in biased engagement with said contact means, said contact means having an extension carrying flow responsive means adapted to be suspended in a fluid passage, said flow responsive means being responsive to fluid flow in the passage to bring about an interruption in said conductive path.

70 3. An electrical switch comprising a body having a fluid passage and a compartment therein in fluid com-

munication therewith, a first conductive element being insulated from said body and extending into said compartment, a second conductive element extending through a wall of said body and being disposed in biased engagement with said first conductive element, said second conductive element having a pivotable extension protruding into a fluid passage, said extension being responsive to fluid flow in said passage to draw said second conductive element away from said first conductive element.

4. An electrical switch for an oil flow indicating system comprising a body with a compartment therein, an external terminal extending through a wall of the body into said compartment forming a first contact therein, a pin contact being in biased engagement with said first contact, said pin contact having an extension through a wall of said compartment in opposed relationship to the entry point of said external terminal, said extension carrying a cup-shaped member in loose engagement therewith whereby a flow of oil in said oil flow indicating system breaks the biased engagement of said first contact and said pin contact by exerting pressure on the cup-shaped member thereby causing a break in the indicating circuit.

5. In combination, an engine oil system, a condition indicating means, and an electrical switch controlling said condition indicating means, said switch comprising a body having apertures in two walls thereof, a terminal pin having a contact formed on one end thereof being insulatedly mounted in one of said apertures, a contact pin slidably disposed in another of said apertures having one end in biased engagement with said terminal pin contact, and flow responsive means projecting into said oil system having a flat plate area attached to a second end of said contact and adapted to be moved when any flow occurs in the oil system thereby levering said contact pin out of biased engagement with said terminal contacts causing a change in said condition indicating system.

6. An oil flow switch comprising a body adapted to be inserted into an aperture in an oil system, said body

5
10
15

having apertures in opposed ends, one of said apertures being adapted to receive and be sealed by an insulated terminal pin, said terminal pin being a conductive path for an indicating circuit and having a contact portion on the inside of said body, a pin disposed in sliding relationship with another of said opposed apertures, said pin having a contact being kept in biased engagement with said terminal contact on one end, said terminal contact and said pin contact closing an electrical circuit when engaged, said pin having an actuator end and extending through said opposed aperture, and an actuator member being loosely carried by said actuator end and having sufficient flat plate area in the oil system to cause a resistance to flow therein, said actuator being pivotable on the base of said body during a flow of oil in the system thereby drawing said pin through said opposed aperture and causing a separation of said terminal contact and said pin contact breaking the circuit therethrough.

7. A flow switch for nonconductive fluids comprising a housing, a plurality of contact means within said housing operable to close an electrical circuit therethrough, one of said contact means being fixed and another of said contact means being in biased and opposed juxtaposition to said fixed contact means, said biased contact means carrying a lever means, said lever means and said plurality of contact means being disposed in a fluid passage and being responsive to fluid flow in said passage to lever said biased contact away from said fixed contact means thereby breaking said electrical circuit.
